AROMATIC-FREE MINERAL OIL RUST
INHIBITING COMPOSITIONSThomas W. Dixon and Lorne W. Sproule, Sarnia,
Ontario, Canada, assignors to Standard Oil De-
velopment Company, a corporation of DelawareNo Drawing. Application March 8, 1951,
Serial No. 214,648

5 Claims. (Cl. 252—395)

1

This invention relates to rust preventing oil compositions and more particularly to oil compositions which tend to inhibit rusting and corrosion of metal and rubber parts.

In connection with the manufacture of anti-freezes from freezing point depressants such as methanol, glycerine, ethylene glycol, denatured ethyl alcohol, etc., experience has indicated that it is necessary to employ a rust inhibitor in the composition. The purpose of the rust inhibitor is to prevent the corrosion of the various metals used in the construction of automotive engines, e. g., aluminum, lead, tin, iron, copper, as well as prevent deterioration of rubber hose used in radiator connections. This corrosion is attributable to the combined action of water and oxygen.

It has now been found that certain specific mineral oil solutions are ideally adapted to provide non-corrosive liquids when added to the before-mentioned anti-freezes.

The ingredients of the mineral oil rust inhibiting solutions are thus as follows: a petroleum mineral oil, ethyleneglycol monobutylether, an oil-soluble sodium petroleum sulfonate and an agent selected from the group consisting of pentaerythritol monooleate or a mixture of sorbitan monolaurate and sorbitan monooleate. The absence of any of these listed ingredients results in unsatisfactory compositions. The components cooperate in obtaining the desired solubility, anti-corrosion and rubber-swelling properties. The quantities of each component have also been found to be critical and are detailed below.

The mineral oils employed are the oils prepared by the well-known exhaustive sulfuric acid treatment of petroleum oil. They are known in the art as Bayol D, Bayol F, etc., which are white petroleum oils and light gas oil fractions that are naphthenic and paraffinic but substantially free of aromatics. They have a viscosity of about 35-60 SUS at 100° F. Mixtures of these mineral oils may also be employed. A typical inspection of Bayol D is as follows:

Specific gravity -----	0.775-0.825
A. S. T. M. Dist., °F.:	
I. B. P. -----	400
F. B. P. -----	505
Mixed aniline point, °F. -----	175
Flash point, °F. -----	160
Unsulfonated residue -----	97%
Sulfur, lamp -----	0.02
Color, Saybolt -----	25
Percent Aromatics -----	Trace

2

The mineral oil is employed in an amount of from 80.5 to 62 weight percent.

Sorbitan monolaurate and sorbitan monooleate must both be employed or, in place thereof, pentaerythritol monooleate alone can be used. These are the only agents that have been found useful in the compositions of this invention for obtaining the desired characteristics. The employment of sorbitan monolaurate without sorbitan monooleate, or vice versa, or the absence of both as well as pentaerythritol monooleate gives undesirable results. Sorbitan monolaurate is employed in an amount of from 3 to 6 weight percent and sorbitan monooleate is employed in an amount of from 0.75 to 1.5 weight percent.

Ethyleneglycol monobutylether is employed in an amount of from 0.75 to 1.5 weight percent. Its absence leads to undesirable corrosion and rubber-swelling characteristics.

An oil-soluble sodium petroleum sulfonate is employed in an amount of from 15 to 30 weight percent. These contribute to the desired solubility and corrosion-inhibiting characteristics. The petroleum sulfonates are prepared by the well-known sulfuric acid treatment of petroleum fractions and the oil-soluble sodium petroleum sulfonates are alkyl aryl sulfonates having a minimum average molecular weight of about 400. The range falls usually between 400-500.

When pentaerythritol monooleate is substituted for sorbitan monolaurate and sorbitan monooleate, the ranges of the ingredients employed are as follows:

	Weight percent
Sodium sulfonates -----	15 to 30
Ethyleneglycol monobutylether --	0.75 to 1.5
Pentaerythritol monooleate -----	2 to 4
Mineral oil -----	82.25 to 64.5

It should be emphasized, however, that no single one of the preceding ingredients insures all the characteristics necessary in the compositions of this invention. The presence of all in the indicated quantities is necessary. This is evident from the examples.

The following examples illustrate this invention and indicate test results obtained on the compositions of this invention.

EXAMPLE I

Rust preventive compositions for anti-freezes

Various compositions were prepared utilizing all the essential components of this invention in the indicated quantities. Formulations were also

prepared omitting individual ingredients as well as those containing all the ingredients but in quantities outside the necessary ranges. The compositions were tested for solubility, corrosion-inhibiting and rubber-swelling characteristics in anti-freezes of water and denatured ethyl alcohol in the following manners.

(a) *Solubility*.—This test was carried out by preparing anti-freeze of the above compositions and centrifuging the mixture for undissolved inhibitor. A trace of undissolved material is allowed.

(b) *Corrosion and rubber swelling*.—The corrosion test was carried out by placing small test pieces of aluminum, copper, iron, tin and a small piece of rubber gasket material commonly used in automobiles in a flask containing equal parts of anti-freeze and water. The flask was equipped with a reflux condenser and maintained at 185° F. for 100 hours. The metal strips were then examined for staining and for plating of one metal to another. The rubber was examined for swelling and softening. The test pieces were not weighed in this test; visual observations were used to evaluate the degree of deterioration. Only slight staining of the metal pieces and no plating of one metal to another is permitted. No deterioration of the rubber is allowed. The results follow.

The compositions must rate "G" on each of the three criteria for commercial acceptability.

neutralize any acids formed by oxidation of the solute.

The aqueous liquids stabilized by the oil compositions according to the present invention are not limited to use in automobile radiators, as they may likewise be used with equal effectiveness in all radiators for gasoline engines, in circulating hot water systems, steam boilers, and in other places where it is desired to prevent corrosion of metal surfaces in contact with aqueous liquids. The quantity of the rust inhibiting oil added to the anti-freeze may be varied as desired.

The corrosion inhibitor of the present invention effectively prevents corrosion of metals without interfering with the heat transfer between metal and the aqueous liquid containing the corrosion inhibitors. Furthermore, the oil is uniformly dispersed throughout the anti-freeze solution and has no tendency to agglomerate in any one particular place, or to clog radiator tubes and the like, as ordinary water-immiscible oils will do in the absence of emulsifying agents.

It is to be understood that this invention is not limited to the specific examples which have been offered merely as illustrations and that modifications may be made without departing from the spirit of this invention.

What is claimed is:

1. A corrosion inhibiting composition comprising a substantially aromatic-free mineral oil containing dissolved therein an oil-soluble sodium

Poor (P)

³ Corrosion test metals Al, Cu, Fe, Sn plus rubber reflux for 100 hours in 50/50 water-alcohol.

Several results are apparent. Experiments designated 1 and 2 indicate that sodium sulfonates plus sorbitan monooleate, or sodium sulfonates plus sorbitan monolaurate and sorbitan monooleate are unsatisfactory in the absence of ethyleneglycol monobutylether. The presence of 1% ethyleneglycol monobutylether, as in experiment 3, gives a very satisfactory rust preventative. Experiment 4 indicates that the reduction by one-half of the sorbitan monolaurate, sorbitan monooleate and ethyleneglycol monobutylether of experiment 3 results in poorer compositions. Experiment 8 shows the necessity for the presence of sodium sulfonates.

Other ingredients may be added to the anti-freeze solutions for various purposes, such as triethanolamine or ortho toluidine, which serve to

petroleum sulfonate in an amount of 15 to 30 weight per cent, ethyleneglycol monobutylether in an amount of 0.75 to 1.5 weight per cent, sorbitan monolaurate in an amount of from 3 to 6 weight per cent and sorbitan monooleate in an amount of 0.75 to 1.5 weight per cent.

mineral oil solution having approximately the following weight per cent composition:

	Per cent by weight	
Oil-soluble sodium petroleum sulphonate	20	5
Sorbitan monolaurate	4	
Sorbitan monooleate	1	
Ethyleneglycol monobutylether	1	
Mineral oil	74	10
	100	

4. A corrosion inhibiting composition consisting essentially of a substantially aromatic-free mineral oil solution having approximately the following weight per cent composition:

	Per cent by weight	
Oil-soluble sodium petroleum sulphonate	20	20
Ethyleneglycol monobutylether	1	
Pentaerythritol monooleate	3	
Mineral oil	76	
	100	25

5. A corrosion inhibiting composition comprising a substantially aromatic-free mineral oil containing dissolved therein an oil-soluble sodium petroleum sulfonate in an amount of 15 to 30 weight per cent, ethyleneglycol monobutylether in an amount of 0.75 to 1.5 weight per cent, and an agent selected from the group consisting of (1) a mixture of sorbitan monolaurate in an amount of from 3 to 6 weight per cent and sorbitan monooleate in an amount of 0.75 to 1.5 weight per cent, and (2) pentaerythritol monooleate in an amount of 2 to 4 weight per cent.

THOMAS W. DIXON.
LORNE W. SPROULE.
